FUEL INJECTION DEVICE FOR INTERNAL COMBUSTION ENGINES

Application filed February 21, 1930, Serial No. 430,288, and in Switzerland March 18, 1929.

This invention relates to fuel injection devices for internal combustion engines and in particular to those which are adapted to be cooled by means of cooling medium preferably in the liquid form.

In such injection devices the cooling medium is usually admitted through a pipe or conduit of relatively small diameter to a chamber or honeycomb surrounding the nozzle of the injection valve, and is thence discharged through a similar conduit. Except in those cases in which the cooling medium employed is a distillate of a high degree of purity, such for example as distilled water, arrangements of this known type have the disadvantage that the conduits by reason of their small internal diameter are liable to become furred or obstructed so that free circulation of the medium is impeded. Further, the chamber around the nozzle necessarily retards the flow and hampers circulation of the medium at this point in the cooling system, thus reducing the cooling effect of the medium on the nozzle and in some cases causing the medium surrounding the nozzle to boil and deposit suspended impurities, such for example as boiler scale.

The object of the present invention is to provide an improved construction of cooled fuel injection device in which the above disadvantages will be overcome.

According to the present invention the cooling medium is conveyed to and from the injection device which rests on a seat fitted in the casing and together with the casing form a tubular cooling chamber through annular chambers arranged one within the other and surrounding the fuel delivery pipe of the nozzle by means of a tubular member subdividing the cooling chamber into two, these annular chambers being in communication with each other at or near the nozzle of the injection valve and one leading cooling medium to, and the other from, the nozzle. The cooling medium during its passage from one chamber to another is sharply deflected over the nozzle and passes over the outer surface of the nozzle at an increased speed so that the transmission of heat from

the injection valve to the medium surrounding the nozzle is accelerated.

One construction of liquid-cooled fuel injection device according to this invention is illustrated by way of example in the accompanying drawings, in which

Figure 1 is a section on the line 1—1 of Figure 3, showing a portion of the engine cylinder cover.

Figure 2 is a section on the line 2—2 of Figure 3, and

Figure 3 is a plan.

In the construction illustrated the cylinder head 1 of the engine carries a casing 2 having at its lower end a cap 3 provided with a conical aperture to receive a fuel injection nozzle 4. The nozzle 4 has a central bore 5 communicating with inclined discharge passages 6 and 7 through which fuel is injected in fine jets 8, 9 into the combustion chamber (indicated at 10).

A fuel delivery pipe 11 having relatively thick walls is in screw-threaded engagement with the inner end of the nozzle 4 and presses the latter on its conical seat in the cap 3, the delivery pipe 11 being in turn held in place by a cover 12 secured to the casing 2 by studs 13 and 14. The fuel delivery pipe 11 has a central bore 15 which communicates with the bore 16 of a fuel supply pipe 17 which passes through a stuffing box 18, 19 in the cover 12.

Screwed into the cover 12 is a tube 25 so dimensioned and arranged coaxial with the fuel delivery pipe 11 that when the injection valve is in position in the casing 2, two annular concentric chambers 20, 21 are provided which communicate with each other at their lower ends. The upper end of the chamber 20 is sealed by means of a packing 22 and the cover 12 encloses the upper end of the chamber 21.

The cooling medium is admitted through a supply pipe 23 in the direction of the arrow 26 and, flowing down the chamber 20, is sharply deflected at the bottom over the nozzle 4, as shown by the arrows 27 and 28. The medium then passes up the chamber 21 and is discharged through a pipe 24 as shown by the arrow 31.

The casing 2 carrying the cover 12 is secured to the cylinder head 1 by means of studs 29 and 30 (Figure 2) and, as will be readily seen from Figure 3, the arrangement of the retaining studs 13, 14, 29 and 30 is such that the injection device occupies the smallest possible space in the cylinder head.

It will be appreciated that with the passages for the medium constructed and arranged according to this invention, the total cross-sectional area available for the flow of fuel is considerably greater than if the cooling medium were conducted through pipes or passages of relatively small internal diameter. The chambers 20 and 21 are preferably circular in cross-section but if desired these may be of elliptical or other cross-section as desired in accordance with any special conditions.

A fuel injection device according to the present invention can be effectively cooled with a medium, such for example as water, which has not been purified or distilled without risk of the passages for the medium becoming sufficiently obstructed to impair free circulation. The fuel injection device described and illustrated has a further advantage that by removing the studs 13, 14, the cover 12 together with the tube 25, the fuel delivery pipe 11 and nozzle 4 can be withdrawn as a unit after which the removal of deposited impurities both inside the casing 2 and on the tube 25 and pipe 11 is a simple matter.

The sharp deflection of the medium over the nozzle 4 as indicated by the arrows 27 and 28 assists the transmission of heat from the nozzle 4 to the cooling medium which surrounds it. The cooling medium in passing up the chamber 21 imparts to the fuel contained in the fuel delivery pipe 11 some of the heat which the medium has taken from the nozzle 4 so that the viscosity of the fuel in the pipe 11 is reduced and the load on the fuel pump reduced accordingly. By reason of the rapid transmission of heat from the nozzle to the medium, evaporation and coking of the fuel in the nozzle is prevented and part of the heat thus imparted to the medium is employed to reduce the viscosity of the fuel before this reaches the nozzle, so that the fuel is maintained at a temperature which is most suitable both for pumping and injection.

I claim:

1. A cooled fuel-injection device for internal combustion engines, comprising a fuel-injector including a nozzle, a casing for the fuel-injector, a seat in the lower end thereof, the injector being mounted in the casing with the lower end thereof resting in said seat and being supported by the casing, said injector being readily removable outwardly from the seat, the injector and casing together defining a chamber for cooling fluid

surrounding the nozzle of the injector, inlet and outlet means in said chamber for said fluid, a tubular member between said casing and said injector and surrounding the injector, the chamber for the cooling fluid being divided into two smaller annular chambers thereby, one of said annular chambers serving to lead the cooling fluid to the nozzle and the other serving to lead the cooling fluid away from the nozzle.

2. A cooled fuel-injection device for internal combustion engines as in claim 1, wherein the two annular chambers adapted for conveying the cooling medium communicate with each other near the nozzle, in such a manner as to accelerate the deflection of the cooling medium at right angles, to thereby accelerate heat-transfer from the injector to the cooling medium.

3. A cooled fuel-injection device for internal combustion engines comprising a fuel-injector including a nozzle, a casing for the fuel-injector, a seat in the lower end thereof, the injector being mounted in the casing with the lower end thereof resting in said seat and being supported by the casing, the injector and casing together defining a chamber for cooling fluid surrounding the nozzle of the injector, inlet and outlet means in said chamber for said fluid, a tubular member between said casing and said injector and surrounding the injector and dividing the chamber for the cooling fluid into two smaller annular chambers which communicate with each other near the nozzle, one of said annular chambers serving to lead the cooling fluid to the nozzle and the other serving to lead the cooling fluid away from the nozzle, and a cover member, said injector, nozzle unit and tubular member being carried by said cover member.

In testimony whereof I have affixed my signature.

HEINRICH DINNER.
